UNITED STATES PATENT OFFICE.

CLINTON B. REPP, OF PLAINFIELD, NEW JERSEY, ASSIGNOR, BY MESNE ASSIGNMENTS,
TO GUILLERMO A. ALONSO, OF NEW YORK, N. Y.

PHONOGRAPH.

1,323,316.

Specification of Letters Patent.

Patented Dec. 2, 1919.

Application filed April 8, 1914, Serial No. 830,339. Renewed April 8, 1919. Serial No. 288,657.

To all whom it may concern:

Be it known that I, CLINTON B. REPP, a citizen of the United States, residing at Plainfield, in the county of Union and State 5 of New Jersey, have invented certain new and useful Improvements in Phonographs, of which the following is a specification, reference being had therein to the accompanying drawings, which form a part thereof.

10 My invention relates to phonographs, and more particularly to the amplifying mechanism thereof.

Heretofore, to secure the desired amplitude of the sound vibrations developed or 15 produced by the diaphragm, it has been a common practice to employ a horn of comparatively large dimensions, having a fairly large bell mouth. Such horns have been made of metal and of wood and the size of 20 the horn has been determined in large measure by the volume of sound desired. In this type of horn the increased amplitude of the reproduction has been secured at the cost of a sacrifice in the clarity, or purity of the 25 tones of the reproduction, which resulted from the development of cross vibrations in the horn itself. By using short "concealed" horns, some of the objectionable characteristics of the larger exposed horns have been 30 eliminated, but the sound reproduction has not been amplified in a degree which will give to the sound waves the desired tone values.

By my present invention, I aim to provide 35 an amplifying mechanism for a phonograph in which the horn structure, while being compact, will give to the reproduced sound the desired amplitude, while preserving the clarity and purity of the reproduced tones 40 through the avoidance of development of discordant vibrations in the material of the horn itself. The dimensions of the horn are such that it may be used either as a concealed horn or as an exposed or outside horn, 45 the differences of use requiring no changes in the dimension of the horn. While a horn made in accordance with my invention includes a plurality of independent communicating ducts, the outlets of which are presented in opposite directions, the construction and arrangement thereof are such that 50 there is no interference of the sound waves moving in opposite directions, or no such interference as impair, or tend to impair, 55 the quality of the reproduced sound. A

horn made in accordance with my invention may be either fixed or movable with relation to the sound box. Furthermore, the independent ducts aside from the means for connecting the horn to the sound box, will be 60 contained one within the other so as to insure a compactness of structure and avoid possibility of such a disarrangement of parts as would lead to a loss in the efficiency 65 thereof.

The invention consists primarily in a phonograph including an amplifying mechanism embodying therein a tubular body of gradually increased dimensions toward the mouth thereof, a closure for the small end 70 of said body, an independent tube mounted within said tubular body, the mouth of which discharges toward said closure, said closure being provided with a means whereby sound waves emitted by said last named tube will be directed radially of said tubular body and means whereby said last named tube may be connected with the sound outlet 75 opening of a sound box; and in such other novel features of construction and combination of parts as are hereinafter set forth and described and more particularly pointed out in the claims hereto appended.

Referring to the drawings:—

Figure 1 is a vertical section of a phonograph embodying my invention as applied to a concealed horn, the horn being shown raised, with the cover, in full lines and lowered in playing position in dotted lines;

Fig. 2 is a horizontal section thereof 90 through the horn;

Fig. 3 is a front view of a modified form of the invention in which the horn bears a fixed relation to the sound box;

Fig. 4 is a vertical section thereof;

Fig. 5 is a longitudinal section of a horn suitable for use as an exposed or outside horn, and

Fig. 6 is a view partially in section of a movable horn in which the inlet is adapted 100 to be automatically connected, or disconnected directly with or from a sound box with the movement of the cover carrying the horn.

Like letters refer to like parts throughout 105 the several views.

In the accompanying drawings I have shown only a portion of the cabinet of a phonograph and only those details of the mechanism necessary to an understanding 110

of the invention. The construction of the turn-table, motor, and reproducing mechanism is immaterial to my present invention which relates more particularly to the amplifying mechanism or the horn forming a part thereof.

In the drawings, I have indicated at *a* the body portion of an ordinary cabinet having a cover *b* which, when opened, exposes 10 the turn-table *c* to facilitate the mounting of a record upon, or its removal from, said turn-table.

The reproducing mechanism which I have indicated at *d* develops vibrations in the 15 amplifying mechanism which mechanism includes a fixed or immovable sound box *d'*, and an amplifier or horn in the novel features of which and more specifically in the manner in which the horn is connected with 20 the sound box, my invention resides.

In the preferred form of my invention shown in Figs. 1 and 2, the cover *b* is hinged to the body *a* of the cabinet, and said cover has firmly secured within the same a tapered 25 tube *e* preferably slightly bellied at the mouth, said mouth opening outwardly of the cover and being closed only when not in use, by the ordinary hinged "lid" *b'*. This tube may be made of metal, wood, or any 30 other desired substance, and it may be circular or angular in cross-section as desired. I have secured very good results with a rectangular tube and also with a circular tube.

35 In the form of the invention shown in the accompanying drawings, the reduced end of the tubular body *e* is fitted to a tapered metallic tubular fitting *f* the taper of which coincides with that of the adjacent portion 40 of the body *e*, the small end of said fitting *f* being provided with a closure *g*. To secure the desired rigidity of the horn mechanism, I provide the cover *b* with a socket *h* within which the closure *g* has a tight driving fit.

45 The sound waves are delivered to the interior of the tubular body *e*—*f* through a tubular elbow, one arm, *i*, of which is substantially axially aligned with the body *e*—*f*, and has its outlet directed toward the closure *g*. I have found that by flaring the arm *i* and reducing it in thickness toward the outlet, bringing it down to a fairly thin edge, I am enabled to increase the intensity 50 of the reproduced sound, as well as to improve its quality or timber. The greatest outside dimensions of the arm *i* are considerably less than the smallest inside dimensions of the adjacent portion of the fitting *f* and the mouth of the said arm *i* is spaced 55 slightly away from the closure *g*, a construction which provides a clearance in front of and about the mouth of said arm. The reverse tapering of the fitting *f* and the arm *i* also insure a gradually increasing clearance 60 from the mouth of said arm toward the

mouth of said fitting by reason of the opposite flare of the outside of said arm and the inside of said fitting.

The other arm *j* of the said elbow projects through the fitting *f* and is firmly secured thereto by a close driven fit, by brazing or in any other desired manner. The protruding end of said arm *j* serves as a means for facilitating the connection of the horn with the sound box.

To avoid a blast at the closure *g* due to the development of vibrations therein upon a plane extending across the mouth of the arm *i*, I provide said closure with a conical, or substantially conical, projection *g'*; the apex of which extends toward, and substantially axially of, the arm *i*. This projection *g'* not only stiffens the closure *g* but divides the sound vibrations emitted by the arm *i* and gives them a direction radially of the axis or center line, of the fitting *f*. I have found that this construction gives highly satisfactory results in use, and the purity and clarity of the reproduced, amplified, sound is increased thereby as compared with other forms of closure.

In the form of the invention shown in Figs. 1 and 2, I mount upon the sound outlet nipple of the sound box *d'*, a tubular fitting, one end *k* of which is mounted upon said nipple. The other end *k'* of said fitting extends parallel with the axis of the hinge of the cover *b*, while the intermediate portion *k*² thereof, connecting the ends *k* and *k'* is projected downwardly in a direction substantially radially of said hinge, and connected to the end *k'*, by a swivel joint *l*, is a similar fitting *m*—*m'* and *m*², the end *m* of which projects upwardly instead of downwardly and is connected with the inlet of the arm *j*. The arms *k'*—*m'* project toward each other, the end of one being rotatably seated within the end of the other which is swelled out to receive it, said ends being held in position by a pin and slot connection indicated at *n* in Fig. 2.

In the modification shown in Figs. 3 and 4 the construction of the horn mechanism is identical with that heretofore described with the exception that the inlet of the arm *j* is in direct connection with the outlet nipple of the sound box *d'*. This construction is capable of use only with a machine in which the horn is at all times fixed with relation to the reproducing mechanism. To permit the mounting of a record upon or its removal from the turn-table *c*, the cover *b* of the cabinet is so constructed as to permit one side thereof to be opened, as by the use of the hinge doors *o*—*o'*.

In Fig. 5, I have shown a horn unattached to the reproducing mechanism the detailed construction of this horn being identical with that heretofore described with the exception that the arm *j* is slightly elongated.

so that when the horn is used as an outside horn, it will be raised sufficiently above the turn-table *c* to permit convenient access thereto.

- 5 In Fig. 6, I have shown a modification of my invention in which the sole difference between the construction thereof and that of the other forms of the invention heretofore described, resides in the forming of the 10 inlet of the arm *j*, so that when the hinge cover *b* is raised or lowered said inlet will automatically be connected with or disconnected from the outlet nipple of the sound box *d'*. This result, in the form of the invention shown, is secured by slightly flaring 15 the end of the arm *j*', although other means for compensating for the arc described by said arm in opening and closing said lid may be used.
- 20 The operation of the herein described amplifying mechanism is substantially as follows, the operation being substantially the same in all of the forms of the invention illustrated, the sole difference being that 25 when the arm *j* is connected with the sound box through the swiveled tubular fittings the sound vibrations must pass through said fittings before entering the inlet tube of the horn, while if said arm *j* be mounted directly upon the sound box there is a direct transmittal of the sound waves from said box to said horn.

When a phonograph embodying my invention is in operation the sound waves developed by the displacement of the diaphragm of the sound box *d'* pass from said sound box and through arm *j* of the tubular elbow, being delivered by the flaring arm *i* against the closure *g*. The substantially 40 conical, raised, central projection *g'* of the closure *g*, will direct the sound waves radially of the fitting *f*, these sound waves thereafter passing through the gradually increased clearance about said arm *i* and between the same and the fitting *f*.

The reduction in the thickness of the arm *i* adjacent the mouth thereof appears to have the two-fold advantage of increasing the amplitude of the reproduced sound, and 50 preventing the development of cross-vibrations due to a surface, represented by the thickness of the stock of said arm, extending parallel with the portion of the closure *g* adjacent the edges thereof.

55 I have demonstrated by actual experience that a horn made in accordance with my invention, the length of which from the bell to the closure *g* is from ten to twelve inches, and the bell of which is about five inches in 60 the circular form, and four by six inches in the rectangular form, will in use produce results which as to the volume or intensity of the sound waves, equal those produced by a twenty-two inch horn having a fifteen inch bell, and that the reproduction will be more

mellow and of greater purity and clarity than with the larger horn.

While an amplifier made in accordance with my invention is particularly adapted for use in connection with an inclosed horn structure wherein the conditions are such as to necessitate a horn of short length, it is not my intention to limit the invention to an inclosed horn structure. Neither is it my intention to limit the invention to the proportions or specific construction of the various parts as shown in the accompanying drawing.

It is to be observed that an amplifier or horn made in accordance with my invention is a compact unitary structure, the parts of which are so assembled and united as to avoid the development of false vibrations therein.

Having described the invention, what I claim as new and desire to have protected by Letters Patent is:

1. A phonograph embodying therein a fixed sound box having a sound outlet and an amplifying mechanism consisting of a tubular body tapering toward the mouth thereof, a cover movable with relation to said sound box, means supporting said tubular body within said cover, a closure for the small end of said body, a tubular member mounted 90 within said tubular body, the mouth of which is directed toward said closure, said closure being provided with means whereby sound waves emitted by said tubular member will be directed toward said tubular body, 100 and tubular means connecting said tubular member with said sound outlet embodying therein a swivel joint permitting movement of said cover and said tubular body supported thereby.

2. A phonograph embodying therein a fixed sound box having a sound outlet and an amplifying mechanism consisting of a tubular body tapering toward the mouth thereof, a cover movable with relation to said sound box, means supporting said tubular body within said cover, a closure for the small end of said body, a tubular member mounted within said tubular body the mouth of which is directed toward said closure, said closure being provided with means whereby sound waves emitted by said tubular member will be directed toward said tubular body, and a tubular fitting, one end of which is connected with said sound outlet, the other end 115 of which extends substantially parallel with the axis about which said cover moves and an intermediate portion of which is directed substantially radially of said axis, and a second tubular fitting one end of which is 120 connected with said tubular member, and the other end of which is aligned and rotatably connected with the end of said first named fitting extending parallel with said axis of said cover.

3. A phonograph embodying therein a fixed sound box having a sound outlet and an amplifying mechanism consisting of a cover inclosing said sound box and movable in relation thereto, said cover having an opening therethrough, a tubular body tapering from the mouth thereof, a closure for the small end of said body, a socket carried by said cover, the mouth of said body being supported by said cover adjacent said opening and said closure being fitted in said socket, a tubular member mounted within said tubular body, the mouth of which is directed toward said closure, said closure being provided with means whereby sound waves emitted by said tubular member will be directed toward said tubular body, and a tubular means connecting said tubular member with said sound outlet embodying therein a swivel joint permitting movement of said cover and said tubular body supported thereby.
4. A phonograph including an amplifying mechanism embodying therein a tubular body comprising a tapering wooden portion adjacent the mouth thereof, and a tapering metallic tubular fitting connected therewith the taper of which coincides with that of said wooden portion, a closure for the small end of said metallic fitting, an independent flared tubular member mounted within said metallic fitting, the mouth of which is directed toward said closure, said closure being provided with means whereby sound waves emitted by said tubular member will be directed toward said tubular metallic fitting, and means whereby said tubular member may be connected with the sound outlet opening of a sound box.
5. A phonograph embodying therein a fixed sound box having a sound outlet, a movable cover inclosing said sound box and an amplifier mechanism consisting of a horn carried by and movable with said cover and means connecting said horn with the sound outlet of said sound box comprising a tubular section in communication with said sound outlet, a tubular member connected with the inlet to said horn and a swiveling connection between said tubular sections whereby said cover may be opened and closed without interrupting the communication between said horn and said sound box.

In witness whereof I have hereunto affixed my signature this fourth day of February, 1914.

CLINTON B. REPP.
